UNITED STATES PATENT OFFICE.

BERNHARD WIENER, OF CHICAGO, ILLINOIS.

ELECTRIC-LIGHT-BATH APPARATUS.

1,162,424.

Specification of Letters Patent.

Patented Nov. 30, 1915.

Application filed June 9, 1915. Serial No. 33,058.

To all whom it may concern:

Be it known that I, BERNHARD WIENER, a subject of the Emperor of Germany, and a resident of the city of Chicago, county of Cook, and State of Illinois, have invented certain new and useful Improvements in Electric-Light-Bath Apparatus, of which the following is a specification.

My invention relates to electric therapeutic apparatus and more specifically to electric light bath apparatus.

The object of my invention is the production of a device of the character mentioned which will be of durable and economical construction, one which may be readily and easily controlled and applied, and one in which will be provided simple and efficient means for effectually guarding the electric lights employed in conjunction with the device.

Other objects will appear hereinafter.

The invention consists in the combinations and arrangements of parts hereinafter described and claimed.

The invention will be best understood by reference to the accompanying drawing forming a part of this specification, and in which,

Figure 1 is a perspective view of an electric light bath apparatus embodying the invention showing the method of employment of the same, Fig. 2 is an elevation showing the interior of the device, and Fig. 3 is a section taken on line $x-x$ of Fig. 2.

The preferred form of construction as illustrated in the drawing comprises a frame 1 formed of a single piece of sheet aluminum which is curved into substantially semi-circular form to adapt the same to partially encircle a portion of the body of the user. As illustrated in the drawing said frame is of a size adapting the same to partially encircle the central or trunk portion of the body of the user, but if desired said frame may be of a lesser size so as to adapt the same for encircling one of the limbs. In other words said frame may be constructed of any size which will best adapt the same for use in connection with the portion of the body in conjunction with which it is desired to employ the device.

Mounted upon the inner side of frame 1 midway the upper and lower edges thereof is a series of spaced electric light supporting sockets 2, each of said sockets being adapted to accommodate two electric lights 3 which

extend upwardly and downwardly from the socket in close proximity with the inner surfaces of frame 1. The sockets 2 are connected in series with a socket 4 which is adapted for engagement with a conventional screw plug for connecting the device with a source of electrical energy.

Mounted upon the front side of frame 1 is a rheostat 5 of conventional construction which is electrically connected with the socket members 2 for controlling the current passing through the lights. Said rheostat is provided with a pivoted handle 6 which controls the resistance offered by the rheostat thereby controlling the strength of the current passing through the lights and hence the intensity of the light and heat of the electric lights. The frame 1 is formed at its upper and lower edges with beads 7 and at its vertical edges with inwardly extending flanges 8 for reinforcement.

Provided at the inner side of frame 1 for coöperation with the electric lights is a guard consisting of two flexible cords 9 arranged adjacent the upper and lower ends of frame 1 at the inner side thereof. The ends of each cord are secured at 10 to the frame 1 adjacent the ends of the latter so that the central portion of the cord is slack. Co-operating with the central portion of each cord is a pair of helical tension springs 11 which connect the same with the adjacent portion of the frame 1 as clearly shown in Fig. 3. With this arrangement it will be seen that each of the guard ropes will be drawn taut and yieldingly held in a position disposed slightly inwardly from the lights in order to serve as a guard against breakage of the lights and also as a guard for the user to prevent burning through contact with the lights when the device is in use. The yieldability of the guard ropes permits of the same conforming with the shape of the body thus conducing to ease and comfort in the employment of the device.

The device is used for the application of light and heat to the diseased or injured portions of the body of the user such as around joints, or the limbs, along the spine or any other part of the body. The device is especially advantageous in the treatment of lumbago, rheumatism, skin diseases, stiff joints, neuritis, gout trouble, etc.

While I have illustrated and described the preferred form of construction for carrying my invention into effect, this is capable of

variation and modification without departing from the spirit of the invention. I, therefore, do not wish to be limited to the precise details of construction set forth, but 5 desire to avail myself of such variations and modifications as come within the scope of the appended claims.

Having described my invention what I claim as new and desire to secure by Letters

10 Patent is:

- 15 1. In a device of the class described, the combination of a frame formed to adapt the same to extend around a portion of the body of the user; electric lights mounted on the inside of said frame; and a yieldable guard at the inner side of said frame for coöperation with said lights, substantially as described.
- 20 2. In a device of the class described, the combination of a frame formed to adapt the same to partially encircle a portion of the body of the user; electric lights mounted on the inner side of said frame; a guard at the inner side of said frame for coöperation with
- 25 30 said lights, said guard comprising an elongated flexible element having its ends secured to said body adjacent the ends thereof so that the central portion of said element is slack; and resilient means engaging with said central portion of said element for yieldingly holding the same drawn taut in a position inwardly of said lights, substantially as described.
- 35 40 3. In a device of the class described, the combination of a frame formed to adapt the same to partially encircle a portion of the body of the user; electric lights mounted on the inner side of said frame; a guard at the inner side of said frame for coöperation with said lights, said guard comprising an elongated flexible element having its ends secured to said frame adjacent the ends thereof

so that the central portion of said element is slack; and helical tension springs connecting said central portion of said element with the corresponding portion of said frame for yieldingly holding the same drawn taut in a position inwardly of said lights, substantially as described.

4. In a device of the class described, the combination of a frame formed to adapt the same to partially encircle a portion of the body of the user; electric lights mounted on the inner side of said frame; a guard at the inner side of said frame for coöperation with said lights, said guard comprising elongated flexible elements arranged at the inner sides of said frame above and below said lights, each of said elements having ends secured to said frame adjacent the ends thereof so that the central portion of said element is slack; and resilient means engaging with said central portion of said element for yieldingly holding the same drawn taut in a position slightly inwardly of said lights, substantially as described.

5. In a device of the class described, the combination of a frame formed to adapt the same to partially encircle a portion of the body of the user; electric light sockets mounted on the inner side of said frame substantially midway the upper and lower edges thereof; and a pair of electric lights mounted in each of said sockets one of which extends upwardly and the other downwardly therefrom, substantially as described.

In testimony whereof I have signed my name to this specification in the presence of two subscribing witnesses.

BERNHARD WIENER.
